SEAT CONSTRUCTION

George H. Hamilton, Grand Rapids, Mich., assignor to American Seating Company, Grand Rapids, Mich., a corporation of New Jersey

Application January 27, 1936, Serial No. 60,976

5 Claims. (Cl. 155—184)

The instant invention relates to seat constructions and more particularly upholstered seats.

The primary objects of the present invention are to provide an upholstered seat which is rugged and sturdy in construction; to provide a seat frame which can be readily and conveniently upholstered and tailored; and, to provide such a seat which is attractive in appearance, utilitarian in use and economical in manufacture.

10 An illustrative embodiment of the invention is shown in the accompanying drawing, wherein:

Figure 1 is a perspective view of the upholstered seat, a portion thereof being opened up to better show the constructional features;

15 Figure 2 is a sectional view of the corner construction of the seat in its unfinished condition but indicating the manner of securing the seat cover to its frame;

Figure 3 is another sectional view of the seat construction in its unfinished condition taken through a corner of the frame but indicating the manner of securing the seat cover to its frame;

20 Figure 4 is a fragmentary top plan view of the corner construction of the seat in its unfinished condition; and

Figure 5 is an enlarged perspective view of the corner plate used in constructing the upholstered seat.

25 Referring to the drawing in which like parts of the seat construction shown are designated by the same numerals in the several views, a rectangular seat frame is here shown as formed from two pairs of wooden elongated members 10, 11, each member of each pair being identical in shape. The opposite ends of each member 10 are arcuately turned in the same direction, the end portion of the side opposite the arcuately turned end of each member 10 being secured to an end of a member 11.

30 A web 12 is spread across the open space defined by the rectangular seat frame and its four borders are each wrapped over a cord 13 disposed adjacent the four upper edges of the frame and to which the four borders of the web 12 are secured in any suitable manner as by tacks 14.

35 A plate 15, here shown as of stamped sheet metal is secured to each end of each of the four elongated members 10, 11 at each corner of the rectangular seat frame. This metal plate has an arcuate grooved portion disposed over and bearing upon and against the covered cord. This plate 15 not only strengthens the seat frame and makes it more rigid and sturdy but it likewise

provides a smooth surface over which the seat cover 16 may be neatly tailored.

This seat cover is here shown as disposed over padding 17 upon the web 12 and over the outer sides of the rectangular seat frame 10, 11 to whose inner sides the four borders of the seat cover may be secured as by tacking to form an upholstered seat. A bottom finishing member 18 in the form of a metal plate may likewise be used if desired which provides added strength and rigidity to the seat frame.

It will thus be seen that the upholstered seat construction herein shown and described is rugged and sturdy in construction, is attractive in appearance and utilitarian in use and that the seat frame may be conveniently and economically upholstered.

While but one specific embodiment of this invention has been herein shown and described, it will be understood that numerous details of the construction shown may be altered or omitted without departing from the spirit of this invention as defined by the following claims.

I claim:

1. A seat construction comprising a rectangular frame formed from two pairs of elongated members, the opposite ends of each member of one pair being turned arcuately in the same direction, the side opposite the arcuately turned end of each member of said pair being secured to an end of a member of the other pair of elongated members, a web spread across the open space defined by the frame whose four borders are each wrapped over a cord disposed adjacent the four upper edges of the frame and to which the four borders of the web are secured, a plate secured to each end of each of the four elongated members at each corner of the rectangular frame having a portion disposed over the cord, and a seat cover disposed over the web and over the outer sides of the rectangular frame to whose inner sides the four borders of the seat cover are secured to form an upholstered seat.

2. A seat construction comprising a rectangular frame formed from two pairs of elongated members, the opposite ends of each member of one pair being turned arcuately in the same direction, the side opposite the arcuately turned end of each member of said pair being secured to an end of a member of the other pair of elongated members, a web spread across the open space defined by the frame whose four borders are each wrapped over a cord disposed adjacent the four upper edges of the frame and to which the four borders of the web are secured, a plate

secured to each end of each of the four elongated members at each corner of the rectangular frame having an arcuate grooved portion disposed over and bearing against the covered cord, and a seat cover disposed over the web and over the outer sides of the rectangular frame to whose inner sides the four borders of the seat cover are secured to form an upholstered seat.

3. A seat construction comprising a rectangular frame formed from two pairs of elongated members, the opposite ends of each member of one pair being secured to the ends of the members of the other pair of elongated members, a web spread across the open space defined by the frame whose four borders are each wrapped over a cord disposed adjacent the four upper edges of the frame and to which the four borders of the web are secured, a plate secured to each end of each of the four elongated members at each corner of the rectangular frame having a portion disposed over the covered cord, and a seat cover disposed over the web and over the outer sides of the rectangular frame to whose inner sides the four borders of the seat cover are secured to form an upholstered seat.

4. A seat construction comprising a rectangular frame formed from two pairs of elongated members, the opposite ends of each member of one pair being secured to the ends of the members of the other pair of elongated members, a web spread across the open space defined by the

frame whose four borders are each wrapped over a cord disposed adjacent the four upper edges of the frame and to which the four borders of the web are secured, a plate secured to each end of each of the four elongated members at each corner of the rectangular frame having an arcuate grooved portion disposed over and bearing against the covered cord, and a seat cover disposed over the web and over the outer sides of the rectangular frame to whose inner sides the four borders of the seat cover are secured to form an upholstered seat.

5. A seat construction comprising a rectangular frame formed from two pairs of elongated members, the opposite ends of each member of one pair being secured to the ends of the members of the other pair of elongated members, a web spread across the open space defined by the frame whose four borders are each wrapped over a cord disposed adjacent the four upper edges of the frame and to which the four borders of the web are secured, a plate secured to each of the two front corners of the rectangular frame, each plate having a portion disposed over the covered cord, and a seat cover disposed over the web and over the outer sides of the rectangular frame to whose inner sides the four borders of the seat cover are secured to form an upholstered seat.
